SPRING-OPERATED SPRAY GUN

George B. Maehren, Seattle, Wash.

Application October 17, 1947, Serial No. 780,414

2 Claims. (Cl. 267—1)

1

This invention relates to a spray gun and an object of this invention is to provide a spray gun or like device in which spring pressure is used to spray liquid from a discharge nozzle.

A further object is to provide a spray gun or like device having a conical spring provided with means which will cause the coil section of the spring to release and expand one section at a time thus providing better and more uniform spring pressure.

Further objects are to provide a spray gun of simple and efficient construction which is not expensive to manufacture, which is easy to operate, which will eliminate the necessity for the use of compressed air in spraying and which is adapted to garden use, paint spraying, fuel spraying or spraying any other liquid.

Other objects will be apparent from the following description taken in connection with the accompanying drawings.

In the drawings:

Figure 1 is a vertical section of a spray gun constructed in accordance with this invention, parts being shown in elevation.

Fig. 2 is a fragmentary sectional view on a larger scale than Fig. 1 showing spring coil holding and releasing devices.

Fig. 3 is a detached perspective of a spring coil holding device.

Fig. 4 is a fragmentary sectional view of an alternative spring.

Like reference numerals designate like parts throughout the several views.

This spray gun comprises a cylindrical receptacle 5 having a removable cap or cover portion 6. Preferably the cover portion 6 is threaded onto the receptacle 5 and a gasket 7 is used to provide a liquid tight seal between these two parts. A piston, which may comprise two plate members 8 and 9 and a cup leather or rubber 10 secured together by screws 11 is provided in the receptacle 5.

A compression spring 12 is provided in the receptacle 5 below the piston for the purpose of urging the piston upwardly. Preferably the spring 12 is made from spring steel of flat rectangular cross section wound spirally so that the coils of said spring will fit one within another when the spring is fully compressed, that is when all of the coils of said spring are in the same plane. The conical spring 12' shown in Fig. 4 is made of spring metal of uniformly decreasing cross sectional area from the larger to the smaller end of the spring. This provides uniformity of stiffness throughout the length of a spring of

2

variable diameter. Spring 12' can be used in place of spring 12. When the spring 12 expands the coils assume a conical form, as shown in Fig. 1. This provides a spring that can be compressed to an over all length substantially equal to the width of one coil. Thus the spring 12 will occupy very little space longitudinally of the receptacle 5 when it is compressed and the over all length of a receptacle 5 of predetermined capacity can be reduced to a minimum.

A spring formed of metal of flat rectangular shape has been found to be more compact when collapsed than a similar spring made from spring wire of round cross section would be. In a hand spray gun using a piston four inches in diameter I have been able to obtain a spring made from metal of flat rectangular cross section capable of exerting a pressure of about four hundred fifty pounds when fully compressed and capable of providing about three and three fourths inches of piston travel.

The means for holding or latching together adjacent laps of the coil of the spring 12 when this spring is compressed and then successively releasing said laps or coil portions as the spring expands, comprises a plurality of curved spring plates 35 each carrying a pin 36. Each pin 36 extends through a small hole 37 in one coil of said spring and is adapted to have its rounded end 38 seat in a substantially semi-spherical recess 39 in an adjacent coil. Preferably the holding devices are installed in offset or staggered relation around the spring. Several of these holding devices are shown in diametrically opposite relation in the drawings. When the spring 12 is fully compressed the pins 36 of all of these holding devices will seat in the respective recesses 39 with which they are aligned. Also when the spring is fully compressed all of the bowed spring plates 35 will be flattened and will lie between the coils of the spring and the pins 36 will be held within their respective notches. As the piston begins to move upwardly the innermost or top coil portion of the spring 12 will begin to move out of engagement with the uppermost holding device. When this occurs the spring plate 35 of this uppermost holding device will begin to assume its normal curved shape and the pin 36 thereof will be retracted and the holding device released. This allows expansion of the coil portions previously restrained by the first holding device and eventually results in a similar releasing of the second holding device. The releasing of successive holding devices continues in this way as the piston moves upwardly until all of said holding devices

have been released. A more desirable spring action has been obtained by thus holding the coil of the spring 12 at spaced intervals and successively releasing the holding devices.

The upper end portion of the spring 12 abuts against the lower side of the lower piston plate 8. Preferably the upper piston plate 9 is relatively thick and preferably the upper surface of said upper piston plate 9 is of convex shape. This thick plate 9 fills most of the space in the cup leather 10 and comes in close proximity to and preferably contacts the cover 6 when the piston is at the top limit of its stroke. Thus it is possible to eject substantially all of the liquid from the receptacle as the piston moves upwardly. Each piston plate 8 and 9 is provided with a centrally disposed threaded opening 13 for receiving the end portion of a threaded piston retracting bolt or screw 14 that is used for retracting the piston. This piston retracting bolt 14 is readily removable after the piston has been retracted and a charge of liquid introduced. The thread on the bolt 14 is diagrammatically shown. I prefer to use a square or acme thread on this bolt but an ordinary tapered thread can be used if desired. A nut 15, preferably provided with a crank arm 16 by which it may be turned, is threaded onto the bolt 14. The nut 15 and arm 16 constitute a threaded crank but obviously an ordinary nut can be used and can be turned with a wrench. When the bolt 14 is to be used to retract the piston said bolt is inserted through a perforation 17 in the bottom 18 of the receptacle 6 and is screwed into the threaded openings 13 of the piston plates 8 and 9. The crank 15-16 is then turned to draw the piston toward the bottom of the receptacle 6 and compress the spring 12.

After the piston has been fully retracted the space in the receptacle 6 above said piston can be filled with liquid, either by removing a plug 4 in the cover 6 or by removing said cover from the receptacle 5. After the receptacle 5 has been filled either the plug 4, or the cover 6 if it has been removed, is applied and sealed. The crank 15-16 is then retracted on the bolt 14 leaving the liquid under the full pressure exerted by the spring 12. The bolt 14 can then be unscrewed from the plates 8 and 9 and removed if desired. Preferably a head 19 is provided on the lower end of the bolt 14 and this bolt 14 can easily be unscrewed from the plates 8 and 9 by reversely rotating the crank 15-16 until the nut part 15 jams against the head 19 and thereafter using the crank 15-16 as a means for unscrewing said bolt 14 from the plates 8 and 9.

The cover 6 has a nozzle member 20 that is provided with a liquid outlet opening 21. A needle type valve member 22 is provided for regulating the size of the opening 21 or for entirely closing said opening 21. An adjustable cap 23 is screw threaded onto the nozzle member 20. The cap 23 is shaped so as to provide a chamber 24 between it and the nozzle member 20. A discharge opening 25 is provided in the cap 23. The shape of this opening 25 determines the shape of the spray that will be emitted. If this opening 25 is of narrow rectangular shape a fan shaped spray will be emitted. If said opening 25 is circular a cone shaped spray will be emitted. The cap 23 is adjustable on the nozzle member 20 and preferably a lock nut 33 is provided to lock said cap 23 in any desired adjusted position. If the cap 23 is moved outwardly on the nozzle member 20 a wider spray will be emitted. If said

cap is moved inwardly on member 20 then a narrower spray will be emitted. The chamber 24 has been found useful in helping to provide a more finely divided and better spray.

The valve 22 extends to the right, Fig. 1, through a tubular fitting 26 and through a packing gland 27 and outwardly to the exterior of the cover 6 and through a forked trigger member 29. The forked trigger member 29 engages within an annular groove 28 in the valve 22. This provides a self adjusting connection between the valve 22 and the trigger 29 so that the valve can be longitudinally moved by movement of the trigger 29 and at the same time said valve is always free to turn and can always stay in correct alignment with the fitting 26. The trigger 29 is pivotally connected by pivot means 30 with a handle 31. The handle 31 is shaped somewhat like the handle of a pistol. The handle 31 is integral with or rigidly connected with the cover 6.

Preferably the outer end portion of the valve 22 extends into an opening 34 in the handle 31. A compression spring 32 is positioned on the valve 22 between the trigger 29 and handle 31. By exerting a pull to the right, Fig. 1, on the trigger 29 the valve 22 can be opened any desired amount and when the valve 22 is thus opened the pressure of the spring 12 will cause a spray of finely divided liquid to be discharged from the opening 25. As soon as the pull on the trigger 29 is released the spring 32 will close the valve 22. Preferably a hook 40 is provided on the handle 31 to facilitate hanging the spray gun on any suitable support. Also preferably finger grips 41 are provided on the handle 31. These grips are useful in preventing turning of the handle 31 in the hand.

This spray gun is particularly well adapted for garden use in the spraying of flowers, vegetables and the like where ordinary hand sprayers are used. However it will be understood that the same can be used for other purposes.

This spray gun can be charged by retracting the piston, removing the plug 4, or removing the entire cover 6, introducing the liquid to be sprayed, replacing and sealing either the plug 4 or the cover 6, and retracting the crank 15-16 to allow the force of the spring 12 to be exerted against the liquid. The bolt 14 will protrude a substantial distance from the bottom of the receptacle 6 when the spring 12 is fully compressed and for this reason said bolt 14 will usually be removed after the gun is filled and before the gun is used for spraying.

In the use of the gun for spraying, the piston will move upwardly as the liquid is discharged and the coils of the spring 12 will be released one after another thereby providing a more constant spring force than I have been able to obtain without the use of the spring holding and releasing devices.

When the piston reaches the upper end of its stroke the convex upper surface of the upper plate 9 will rest against the cover 6 as shown in Fig. 1 and the piston will be stopped before the spring 12 is fully expended and while there is still a strong pressure exerted by said spring.

The foregoing description and accompanying drawings clearly disclose a preferred embodiment of my invention but it will be understood that changes in the same can be made within the scope of the following claims.

I claim:

1. In apparatus of the class described, a coni-

cally shaped spirally wound one piece compression spring adapted to be interposed between two relatively movable members, said spring being formed of flat spring metal of substantially rectangular cross section and the coils of said spring being adapted to telescope relative to each other when the spring is compressed, whereby the spring will occupy a minimum amount of space; coil holding latch means carried by coil portions of said spring; and latch receiving recesses provided in other coil portions of said spring adjacent to and in registration with the latch means when said spring is compressed, the latch means being adapted to engage within the recesses and releasably connect the coil portions of said spring together when the spring is compressed and to release the coils of said spring successively from one end of the spring as said spring expands.

2. In apparatus of the class described, a conically shaped spirally wound one piece compression spring adapted to be interposed between two relatively movable members, said spring being formed of flat spring metal of substantially rectangular cross section and the coils of said spring being adapted to telescope relative to each other when the spring is compressed whereby the spring will occupy a minimum amount of space, coil portions of said spring having transverse perforations provided therein and other coil portions of said spring having approximately semi-spherical recesses positioned in alignment with said transverse perforations; latch pins slidably disposed in said transverse perforations, each

5 latch pin having one rounded end portion adapted to engage within an adjacent semi-spherical recess; and a concavo-convex latch pin spring of flat metal attached to the other end portion of each latch pin with the concave side thereof toward the latch pin and with the latch pin spring operatively disposed between adjacent coil portions of the compression spring, whereby when said compression spring is compressed the latch pin springs will be flattened between adjacent coil portions of the compression spring and the rounded end portions of the latch pins will be engaged within the semi-spherical recesses and will releasably latch the coil portions of said compression spring together, and whereby as said compression spring expands the latch pin springs and latch pins will be released successively from one end toward the other of said compression spring and will successively release the coils of said compression spring.
